INTERLOCKING JEWELRY CLASP

Paul Gaston, New York, N.Y., assignor to Royal of Pittsburgh, Inc., Pittsburgh, Pa., a corporation of Pennsylvania

Filed Apr. 1, 1964, Ser. No. 79,302

Term of patent 7 years

(Cl. D45—4)

FIGURE 1 is a top plan view of an interlocking jewelry clasp showing my new design;
 FIG. 2 is a side elevational view thereof;
 FIG. 3 is an end elevational view thereof;
 FIG. 4 is an exploded end elevational view thereof;
 FIG. 5 is an exploded top perspective view thereof;
 FIG. 6 is a top plan view of another embodiment of my new design wherein the outline configuration is square.

I claim:

The ornamental design for an interlocking jewelry clasp, as shown and described.
